UNITED STATES PATENT OFFICE.

LEON E. LA BOMBARD, OF CHELSEA, MASSACHUSETTS, ASSIGNOR TO SPECIALTY AUTOMATIC MACHINE COMPANY, OF CHELSEA, MASSACHUSETTS, A CORPORATION OF MASSACHUSETTS.

MACHINE FOR MAKING COMPOUND BOXES.

1,370,654.

Specification of Letters Patent.

Patented Mar. 8, 1921.

Application filed February 24, 1917. Serial No. 150,679.

To all whom it may concern:

Be it known that I, LEON E. LA BOMBARD, of Chelsea, in the county of Suffolk and State of Massachusetts, have invented certain new 5 and useful Improvements in Machines for Making Compound Boxes, of which the following is a specification.

This invention relates to the manufacture of paper boxes, the present application being a continuation of my earlier application 10 Serial No. 69942, filed January 3, 1916, now Letters Patent 1,285,007 granted November 19, 1918, in so far as the claims cover subject matter disclosed in the earlier application. The invention relates particularly to 15 the manufacture of paste board boxes comprising two members or blanks one of which is considerably larger than the other and forms the bottom and top and the inside 20 walls of the box; the other member or blank being smaller and in the general form of a strip which, when the box is "set up" for filling, incloses the end and front walls of the main or larger member. Boxes of this 25 type are commonly referred to as candy boxes since they are very largely employed for containing candy sold at retail. The boxes are kept in stock in flat condition and are set up by the employees of the dealer 30 before filling. Boxes of this type would be very expensive to make, if made, each from a single blank, because there would be a great waste of material in cutting out the blanks.

35 Hence it is customary to make such boxes of two blanks or members which are adhesively connected. So far as I am aware, the assembling of the blanks in pairs, so as to fit them to be afterward set up into recep- 40 tacle form to hold goods, has only been done by hand.

The principal object of this invention is to provide a simple and rapidly operating machine which will automatically and accurately assemble and unite the two blanks of a box, the machine turning out the product in flat condition, convenient for shipping and storing.

With the above and further objects in view my invention consists in the improvements which I shall now proceed to describe and claim:

Of the accompanying drawings:

Figure 1 is a plan view of the essential 55 parts of a machine embodying my invention.

tion, the upper feed devices being omitted to permit parts below to be shown.

Fig. 2 is an elevation of the same, including the upper feed devices.

Figs. 3 and 4, on two sheets because of the 60 larger scale, taken together, represent a longitudinal section of the machine.

Fig. 5 is an elevation, from the opposite side, of that portion of the machine which is shown in Fig. 3.

Fig. 6 is a detail plan of a portion of the mechanism shown in Fig. 5.

Fig. 7 is a sectional detail looking from the right of Fig. 6.

Fig. 8 represents a detail section on line 70 8-8 of Fig. 4, on a larger scale.

Fig. 9 represents a detail section on line 9-9 of Fig. 3 on a smaller scale.

Fig. 10 represents a detail section on line 75 10-10 of Fig. 3.

Figs. 11 to 15 are diagrammatic views to illustrate successive operations of the machine on the blanks.

Figs. 16 and 17 are, respectively, plan 80 views of the body and band blanks.

Fig. 18 is a perspective view of the body blank in the angularly bent form in which it passes through the machine.

Fig. 19 represents the two blanks in the relative positions which they occupy as they 85 approach each other to be joined.

Fig. 20 represents the two blanks after being joined.

Fig. 21 is a perspective view of a box set 90 up for use.

Similar reference characters indicate similar parts in all of the views.

The frame of the machine includes side bars 25, and suitable tie rods and leg supports.

The wide blanks *a* are fed one at a time from the bottom of a pile in the lower hopper 26, by a feed wheel 27 carried by shaft 28 and having friction plugs 29 in its periphery. Each blank then passes under a 100 belt 30 mounted on a pulley 31 carried by shaft 28 and a small pulley 32 carried by a suitably supported bracket 33 (see Fig. 3).

A lower belt 34, which is not positively driven, is mounted on suitably supported 105 rolls 35, 36. The belt 34 is not directly underneath belt 30, but at one side of the vertical plane thereof (see Figs. 1 and 10). This is to avoid taking any such grip on the blank, while advancing it, as to prevent the 110

blank from being straightened out as presently described. The upper stretch of belt 34 is supported by a strip 37 carried by side bars 38 (Fig. 10) so that the blank will be 5 supported in proper position while the twist belt 39 "breaks down" a side portion of the blank on one of its creased lines (Fig. 10). The twist belt is mounted on and driven by a pulley 40 (Fig. 5) carried by shaft 28 10 close to feed wheel 27 (Fig. 1), said belt running over a roll 41 carried by a suitably supported arm or bracket 42 the roll 41 being mounted to rotate on an axis at the proper angle to give such twist to belt 39 15 as to cause its inner stretch to act on the portion α' of the blank to "break" it down to vertical position. The gradual twist of the operative stretch of the belt is such that if the blank is "askew", it will straighten it 20 out as it leaves the influence of said belt because, at such point, the portion of said stretch has reached a vertical position close to one of the bars 38.

The belts 30, 34, 39 travel at substantially 25 the same speed, but do not so grip a blank as to prevent it from being straightened out by the action of twist belt 39 bearing against it at the angle between portions α , α' . In other words, if the blank enters askew, the 30 portion α' is bent down (Fig. 10) just the same, and the inner line of the angle will be caused to aline with the edge of belt 34. This action would be interfered with if the part 30 did not travel. That is, if it were 35 a stationary guide finger or shoe, the friction between it and the blank would tend to cause the blank to become askew even if started straight. For these reasons, I provide the two carrying belts 30, 34, traveling substantially side by side, and not tightly gripping the blanks, so the twist belt 39 can readily perform its described function.

Just as the blank is leaving the influence of the twist belt, its down turned portion 45 passes behind a vertical guide plate 43; that is, it passes between said guide plate and the adjacent bar 38 and enters between a feed chain 44 and a long guide bar 45 (Figs. 6 and 7). Said chain is mounted on sprockets 50 46, 47, mounted on or carried by vertically mounted stud shafts, the shaft for sprocket 47 being driven by suitable gearing to cause the chain to travel in the direction of the arrow in Fig. 1. This chain carries, at suitable 55 intervals, hook-shaped lugs 48 to engage the vertical portions of the rear edges of the blanks. Each blank, when it is delivered to position to be acted on by a hook 48 of the chain, is free from any other 60 warding or advancing influence, because it has passed beyond belts 30, 34, and remains a moment as indicated in Figs. 7 and 18 until a hook 48 reaches or "catches up with" the rear edge of the down-turned portion 65 α' . Then said hook will feed or push it

along at a uniform speed without liability of its twisting or turning. Owing to the bent form of the blank, as in Fig. 18, and the fact that the blank is so guided that it retains this bent form, a single chain with 70 lugs will feed it accurately. The reason for effecting the travel of the blanks α along this portion of the machine by the chain lugs 48 engaging the vertical instead of horizontal portions of the blanks is that, as 75 presently described, an adhesive is applied to the tongues α^2 , α^3 of each blank, which tongues are parts of the horizontal portions of the blanks. And one of said tongues (α^2) is turned up and backwardly (Figs. 80 3 and 20). For obvious reasons these later treatments of horizontal portions of the blanks would be interfered with if said portions were to be engaged by feeding lugs. The lower edge 49 (Fig. 7) of the long 85 superstructure bar 50 (Figs. 1, 3 and 5) slightly overlaps the angle of the blank, and a guide strip 51 supported by suitable arms (Fig. 7) depending from cross or tie rods of the machine, directs the horizontal portion of the blank properly.

As the blank α is now pushed along, a suitable adhesive, hereinafter referred to as glue, is applied to the under surface of each of its tongues α^2 , α^3 , by the glue pads 52 carried by arms 53 revolving in a glue box 54. One arm is carried by a shaft 55 (Fig. 9) mounted in an outer or sleeve shaft 56 which carries the other arm. The outer shaft is positively rotated (see Figs. 1 and 2) and 100 the inner shaft is clamped or set therein by any suitable means which will permit the inner shaft to be rotatively adjusted so that its arm 53, instead of being radially opposite the other arm as in Fig. 3 will be at a 105 more or less obtuse angle relatively thereto. By a dial and pointer arrangement such as indicated in Fig. 2, the degree of angle may be determined. The object of this adjustment of one pad relatively to the other 110 is to adapt the glue pads to properly act upon blanks of varying lengths. This is because one of the two pads applies glue to the under surface of the front tongue α^2 and the other pad to the under surface of 115 the rear tongue α^3 of the same blank. (See dotted areas Fig. 16). The timing of the driving parts of the machine is such that a hook lug 48 of feed chain 44 takes control of a temporarily stationary blank just 120 in time to push it along and bring its tongue α^2 over one pad as the latter reaches its highest position, the other pad then coming up under the rear tongue α^3 . A suitable adjustable scraper, indicated partly by dotted 125 lines in Fig. 3 is employed to control the thickness of the glue transferred by the pads.

After the tongues have received their spots of glue the front tongue α^2 is turned up and over to present its glued area upper- 130

most to receive thereon the front end of the strip or band blank *b*, the feed of which will be hereinafter explained. As the blank *a* is fed along, it passes under spring pressers 57 (Figs. 3 and 12) which not only hold the blank in a plane to insure proper application of glue by the rotary pads, but also hold the body portion of the blank down to resist the lifting tendency of the tongue bender, so that said tongue will bend up on its creased line. The tongue bender consists of an arm 58 pivoted at 59 and having a hook 60 which is normally held in the path of the approaching edge of the tongue by a spring 61. As the blank is pushed along, the spring yields and the arm and hook swing up as shown in Figs. 3 and 12, the hook carrying the tongue *a*² up and holding it during continued feed of the blank so that said tongue is laid back with its glued area under the end *b*' of blank *b* which is now approaching it in a downwardly inclined direction. (Figs. 12 and 19).

Before proceeding further with the description of the travel of blanks *a*, I will describe the properly timed feed of the blanks *b* to bring them into proper assembly with blanks *a*.

A suitably supported hopper 62 is shown in Figs. 2 and 3, but is omitted from Fig. 1, to avoid concealment of parts below. The long band blanks *b* are fed, one at a time, from the bottom of a pile in hopper 62, by a feed wheel 63 similar to the feed wheel 27, carried by shaft 64 mounted in an upwardly projecting portion of the rigid bar 50. Also carried by shaft 64 is a sprocket wheel 65 for chain 66 which is driven by a sprocket 67 (Figs. 2 and 4) carried by shaft 68. The chain has suitably spaced lugs 69. The blanks are fed by the wheel 63 over an adjustable retard 70 similar to one which extends under wheel 27, and over an idle roll 71 and guide 72 pivoted at 73 and adjustable by a screw 74.

Each blank fed over the guide 72 passes over a guide strip 75 and under belt 77 presently described. During this movement, blank *b* travels in a downwardly inclined direction, the chain 66 passing under an adjustably mounted sprocket 76. Traveling parallel with the operating stretch of chain 66 for the greater part of its length, is a belt 77 mounted on pulleys 78, 79, the pulley 78 being carried by a shaft 80 having a sprocket driven by a chain 81 which, in turn, is driven by a sprocket wheel carried by shaft 64. A series of pairs of rolls 82 insure proper travel of the belt 77.

The connections just described are such that the belt 77 travels faster than chain 66. The friction of the belt on the blanks is not heavy, but is sufficient to insure the movement of each blank until its front edge "catches up to" a lug 69 (Fig. 4), after

which belt 77 slips on each blank and keeps its front edge in contact with lug 69. The timing is such that blank *b* arrives in the position indicated at the left end of Fig. 4 with its front end *b*' above the bent over tongue *a*² of blank *a*.

The next operation is to bend the rear end *b*² of the long blank *b* down and carry it up against the under surface of tongue *a*³ of blank *a*. A chain 83 (Figs. 2 and 4) is mounted on sprocket wheels 84, 85, the shaft 86 of the latter being actuated to drive the chain 83 faster than the speed of the blanks for a reason presently described. At two or more places, the continuity of the chain 83 is interrupted by devices which, for convenience I term pockets. Each pocket consists of two U-shaped bars 87 which take the place of one or two links of the chain. The two bars of each pocket are side by side but spaced as indicated in Fig. 8 to enable said pockets to be carried around the sprockets. Each pocket carries a pivoted hook 88 held by a spring normally in the position shown in Fig. 4, with the hook projecting slightly out from the chain.

A finger 89 is carried by a short rock shaft 90 having an arm 91 provided with a roll 92 engaged by a cam 93 formed in one side of sprocket 76 (see dotted lines, Fig. 4). Said cam acts to hold finger 89 raised while the two blanks of the pair are passing under it, and to permit said finger to be swung suddenly down by a suitable spring 94, to the position shown in Fig. 13 just as the rear end *b*² of blank *b* arrives under it. This movement of finger 89 knocks the end *b*² down and carries its rear edge to position to be caught by the hook 88. As the chain 83 travels faster than the blanks which are now in contact with each other, and as the spring of hook 88 is a very light one, said hook readily yields downward and carries the rear section *b*² down (see Fig. 14), the pocket 87 permitting this. As the hook 88 swings down, it slightly bends the section *b*² over the front edge of the pocket, thus insuring a proper fold of said section.

Then the upward tendency of hook 88, and finally the rear edge of the mouth of the pocket (which, as stated, is traveling faster than the blanks), carries the section *b*² up against the under (glue coated) surface of the tongue *a*³ of blank *a* (Figs. 15 and 20). This finishes the fold of section *b*². After the section *b*² has been folded up as described, the assembled blanks are directed by a guide 95 (Fig. 4) to the nip of two pressing rolls, the upper one of which is carried by shaft 68, and the lower one by a shaft 96. The blanks are then directed by another pair of rolls carried by shafts 97, 98, to any suitable receptacle or to a pair of delivery belts 99, 100, mounted on pulleys carried by shafts 101, 102.

The pressure rolls travel, peripherally, slightly faster than the speed of the hook lugs 48 of the side chain 44, and therefore, as soon as the front ends of the assembled 5 blanks reach the nip of the first pair of presser rolls, said rolls begin to draw the blanks away from the hook lug which is acting on the rear edge of portion *a'* of blank *a*. By the time the said rear edge 10 reaches the pressure rolls, there has been sufficient advance of the blanks to entirely clear said rear edge from the hook 48 with which it had been engaged so that when said hook passes around the sprocket 47 (Fig. 1) 15 it can not, as it moves away, carry the edge of the blank with it and tear it.

After the machine has joined the two blanks as shown in Fig. 20, each compound box so made is usually folded flat for shipment, such fold being made on the crease 20 line which, in Fig. 18, defines the angle where the main or larger blank is bent. To set up such a box for use it is manually unfolded sufficiently to permit the four wall 25 flaps of blank *a* to be turned up at a right angle to that portion which is to form the bottom of the box, and then the blank *b* is opened out and swung to position to inclose the end and front walls as shown in Fig. 21.

30 This manual operation is well understood by all candy store people.

As the invention claimed herein is not affected by any particular system of gearing and shafting, it will be unnecessary to 35 describe the details of the driving mechanism for the machine and its various parts, especially since the drawings quite clearly show such mechanism. And since the operations of the different parts of the machine 40 have been described in connection with the description of their structures and mounting, an explanation of the operation of the machine as a whole is unnecessary.

Having now described my invention in 45 one of its embodiments, although without attempting to illustrate or describe all of the modifications or variations thereof, what I claim is:

1. A machine for making paper boxes, 50 comprising means for bringing a pair of blanks into surface contact with each other, and means for connecting the blanks together at separated points leaving major portions of the blanks unconnected, whereby 55 the united blanks may be opened up to form a box.

2. A machine for making paper boxes from pairs of blanks, said machine comprising means for transversely folding both 60 blanks of each pair, means for assembling the two blanks after such folding, and means for connecting the blanks together at separated points leaving major portions of the blanks unconnected, whereby the

65 united blanks may be opened up to form a box.

3. A machine for making paper boxes, 70 comprising means for bringing a pair of blanks into surface contact with each other, and means for adhesively connecting the 75 blanks together at separated points leaving major portions of the blanks unconnected whereby the united blanks may be opened up to form a box.

4. A machine for making paper boxes 75 from pairs of blanks, said machine comprising means for transversely folding both blanks of each pair, means for assembling the two blanks after such folding, and means for adhesively connecting each folded 80 portion of one blank to a flat surface of the other blank leaving major portions of the blanks unconnected whereby the united blanks may be opened up to form a box.

5. A machine for making paper boxes, 85 comprising two hoppers for blanks, means for feeding blanks singly from each of the hoppers, means for bringing the blanks from the hoppers together in completely 90 overlying flat relationship, and means for connecting the blanks together at separated points leaving major portions of the blanks unconnected.

6. A machine for making paper boxes comprising two hoppers for blanks, means 95 for feeding blanks in pairs, one from each of the hoppers, means for doubling or folding over portions of one blank of each pair, means for applying adhesive to portions of one blank in position to adhesively connect 100 the folded over portions of one blank to the other blank when the two are brought together, and means for bringing said two blanks together in flattened relationship.

7. A machine for making paper boxes, 105 comprising two blank hoppers in alinement, means for feeding blanks singly from each of the hoppers, means for causing the blanks to travel in the same direction in pairs, one above another, and means for connecting the 110 two blanks of each pair at isolated points while said blanks are traveling.

8. A machine for making paper boxes, comprising two blank hoppers in alinement, means for feeding blanks singly from each 115 of the hoppers, means for causing the blanks to travel in the same direction in pairs, one above another, means for applying adhesive to separated portions of one blank of each pair, and means for pressing the pairs of 120 blanks together while traveling.

9. A machine for making paper boxes each of which consists of a strip blank and a body blank having tongues, said machine comprising separate hoppers for the two 125 kinds of blanks, means for feeding blanks from the two hoppers in timed relationship, means for assembling the blanks in pairs,

and means for adhesively securing the ends of the strip blanks to the tongues of the body blanks.

10. A machine for uniting blanks to make compound boxes, comprising a plurality of hoppers for the blanks, means for feeding blanks from the hoppers in timed relationship, means for folding over or doubling portions of the blanks, and means for applying adhesive to limited areas of the blanks in locations to retain the blanks together with their folded portions secured.

11. A machine of the character described, comprising two hoppers for the blanks, means for feeding a pair of blanks in timed relationship one from each of the hoppers, means for applying limited areas of adhesive to different portions of one of the pair of blanks, means for turning over a portion 20 of each blank, and means for assembling and compressing the two blanks together.

12. A machine of the character described, comprising two hoppers for the blanks, means for feeding a pair of blanks in timed relationship one from each of the hoppers, means for applying limited areas of adhesive to different portions of one of the pair of blanks, means for turning up and bending over one portion of one blank, means for 25 turning a portion of the other blank down and bending it underneath, and means for assembling and compressing the two blanks together.

13. A machine for making paper boxes, comprising two blank hoppers in alinement, means for feeding blanks singly from each of the hoppers, means for causing the blanks to travel in the same direction in pairs, one above another, rotative means for applying adhesive to separated portions of one blank of each pair while traveling, and means for 30 pressing the pairs of blanks together.

14. A machine for making paper boxes, comprising two blank hoppers in alinement, means for feeding blanks singly from each of the hoppers, means for causing the blanks to travel in the same direction in pairs, one above another, a pair of rotary glue pads spaced to apply glue to separated portions 45 of one blank of each pair while traveling, and means for pressing the pairs of blanks together.

15. A machine for making paper boxes, comprising two blank hoppers in alinement, means for feeding blanks singly from each of the hoppers, means for causing the blanks to travel in the same direction in pairs, one above another, a pair of rotary glue pads spaced to apply glue to separated portions 55 of one blank of each pair while traveling, means for adjusting the positions of said pads relatively to each other, and means for pressing the pairs of blanks together.

16. A machine for making paper boxes, comprising two blank hoppers in alinement,

means for feeding blanks singly from each of the hoppers, means for causing the blanks to travel in the same direction in pairs, one above another, means for applying adhesive to front and rear portions of the lower blank of each pair, a yielding folder having a portion to engage the edge of said lower blank and turn it over, and means for pressing the pairs of blanks together.

75

17. A machine for making paper boxes, comprising two blank hoppers in alinement, means for feeding blanks singly from each of the hoppers, means for causing the blanks to travel in the same direction in pairs, one above another, means for applying adhesive to front and rear portions of the lower blank of each pair, a pivoted hook to engage a front edge portion of the blank and turn it over, a spring to cause the hook to double 80 said portion over on the body of the blank, and means for pressing the pairs of blanks together.

85

18. A machine for making paper boxes, comprising two blank hoppers in alinement, means for feeding blanks singly from each of the hoppers, means for causing the blanks to travel in the same direction in pairs, one above another, means for applying adhesive to front and rear portions of the lower blank of each pair, means for turning the front adhesive-bearing portion of said lower blank over on the body of the blank, a folder for doubling over the rear portion of the upper blank of each pair, and means for 90 pressing the pairs of blanks together.

95

19. A box-making machine having a carrier for advancing blanks successively, and a folder for doubling over the rear portions of the blanks while the latter are traveling, a movable support being provided to aid the folder in determining the line of fold.

105

20. In a box-blank folding machine, a guide for the blanks, means for advancing the blanks, means for bending a portion of each blank at an angle to the rest of it, and means contacting with the bent portion of each blank to insure its advancing straight relatively to said guide.

110

21. In a box-blank folding machine, a guide for the blanks, means for advancing the blanks, a twist belt arranged relatively to said guide to bend a portion of each blank at an angle to the rest of it and press said bent portion squarely up against the 115 side of said guide.

120

22. In a box-blank folding machine, three belts for acting on the blanks, two of the belts having their acting portions side by side to carry the blanks, the third belt being 125 twisted and crossing the plane of the acting portions of the carrying belts at an acute angle to said plane to bend a portion of each blank and press it laterally to insure its passing through the machine straight.

130

23. In a machine of the character described, a pair of endless carriers having their operative stretches side by side, one of said carriers having lugs and the other having a friction surface, means for driving the friction carrier faster than the carrier having the lugs, whereby the front edges of blanks contacting with said carriers will be caused to abut said lugs, and means for doubling the rear portions of the blanks in a forward direction.
24. In a machine of the character described, a belt, an endless chain having lugs, the operative stretches of the belt and chain being side by side, means for driving the belt faster than the chain to cause the front edges of blanks to abut the lugs accurately spaced, and means for doubling the rear portion of each blank in a forward direction while traveling.
25. In a machine of the character described, an endless carrier having a pocket, means for causing a blank to travel in a plane substantially parallel with said carrier, means for deflecting a portion of the blank toward said pocket, and means connected with said carrier to engage said deflected portion and bend or fold it to a further extent.
26. In a machine of the character described, an endless carrier having a pocket, means for causing a blank to travel in a plane substantially parallel with said carrier, means for deflecting a portion of the blank toward said pocket, and a yielding hook connected with said carrier to engage the edge of said deflected portion and carry it into said pocket.
27. In a machine of the character described, blank-carrying means, an endless chain having a pocket, a yielding hook adjacent said pocket, means for deflecting the rear end of the blank to position to be engaged by said hook, and means for driving said chain at a speed faster than that of the blank-carrying means.
28. In a machine of the character described, blank-carrying means, an endless chain having a pocket, a yielding hook adjacent said pocket, means for deflecting the rear end of the blank to position to be engaged by said hook, said hook being located relatively to the mouth of the pocket to bend the deflected portion of the blank over the front of said mouth, and means for driving said chain at a speed faster than that of the blank-carrying means.
29. In a machine of the character described, an endless carrier having a pocket, means for carrying a blank to travel in a plane substantially parallel with said carrier, means for deflecting a portion of the blank toward said pocket, said means comprising a vibratory finger with actuating devices to cause it to operate with proper timing, a yielding hook connected with the carrier to engage the edge of said deflected portion, and means for driving said carrier at a speed greater than that of the blank.
30. In a machine for making boxes, means for bending a blank to angular form with substantially horizontal and vertical portions, a single carrier having a lug to engage the rear edge of the vertical portion of the blank at one side of the bend thereof, means for applying adhesive to a horizontal portion at the other side of said bend, and means for guiding said blank in its angular form.
31. In a machine for making boxes, means for feeding blanks singly in horizontal or flat position, means for bending a portion of each blank to substantially vertical position, a chain having lugs spaced to cause one lug to engage the rear edge of the vertical portion of each blank, means for operating on the horizontal portions of the blanks, and means to guide the angularly bent blanks while pushed along by said lugs.
32. In a machine for making boxes, means for feeding blanks singly, means for bending the blanks angularly, an endless carrier having hook-shaped lugs to engage the rear edges of the blanks at one side of the angular bends thereof, means for uniting other blanks to the bent blanks, and pressure rolls provided with means for causing them to rotate with a peripheral speed in excess of the speed of travel of the lug-carrier to disengage the blanks from the lugs after said uniting.
33. A machine of the character described, comprising means for feeding and bringing into juxtaposition pairs of dissimilar blanks, one blank of each pair being long and narrow and the other having a tongue at each of its front and rear edges, means for applying glue to the under surface of each tongue, means for folding the front tongue of each pair to lap the front end of a long blank, means for folding the rear end of each long blank to lap the rear tongue of its companion blank, and means for pressing the pairs of blanks.
34. In a machine for uniting two dissimilar blanks to make boxes, a pair of endless lug-carriers, means for supplying blanks of one kind to position with front portions thereof contacting with the lugs of one carrier, means for supplying blanks of the other kind to position with the lugs of the other carrier contacting with rear portions of said blanks, means for applying adhesive to front and rear portions of one of the pairs of blanks, and means for pressing the pairs of blanks together.
- In testimony whereof I have affixed my signature.
